No. 1.033.

George Bruce Des 1033
Design for Printers Types.

A real-Spirited & emphatic Script. Patented Aug. 10. 1858.

New York, July, 1858.

The great success achieved by my Copeyed Script of 1856, has induced me to cut this Grand-Size letter, in
which you see, patented Oct. 6, 1858, has induced me to cut this Grand-Size letter, in
a somewhat similar style, but I have claimed it as a distinct letter for Cicero, Standard, Grecian, and
most elsewhere. It will be found a very distinct letter for Cicero, Standard, Grecian, and
other small jobs. Though from its light character it can hardly aspire to the dignity of formal
or Grand for the emperors of France
My government of Military Characters, extending from Canon to
Pica in various sizes, is the most complete in the world, and for fine proportion and grace-
ful turn the new font, of which this is one, is unequalled. Type will be at home or abroad
sent on special order with the usual protection, they are printed on an
even surface.

Yours truly
Geo. Bruce

SCRIPT.

Des. 1033

George Bruce, of New York, N.Y.
Letters Patent No 1033 - dated Aug. 10. 1858.

The schedule referred to in these Letters Patent and making part of the same.

To all whom it may concern:

Be it known that I, George Bruce, of the City and County of New York, in the state of New York, have invented or produced a new set of printing types, for letter-press printing, of a new and original design which I describe as follows, reference being had to the annexed printed impression thereof. It is of the kind usually called Script and of the size usually called Great Primer, but it differs from every other Script type in shape size and proportion.

I call this new type Great Primer Copperplate Script, and I claim the design of the said type as described and shown.

Witnesses.

D.W. Bruce
